UNITED STATES PATENT OFFICE.

HENRY M. WHEELWRIGHT, OF WARE, MASSACHUSETTS, ASSIGNOR TO FECULOSE COMPANY OF AMERICA, OF WORCESTER, MASSACHUSETTS, A CORPORATION OF MASSACHUSETTS.

APPARATUS FOR SIZING PAPER.

1,258,840.

Specification of Letters Patent. Patented Mar. 12, 1918.

Application filed June 28, 1916. Serial No. 106,499.

To all whom it may concern:

Be it known that I, HENRY M. WHEELWRIGHT, a citizen of the United States, residing at Ware, in the county of Hampshire 5 and State of Massachusetts, have invented a new and useful Apparatus for Sizing Paper, of which the following is a specification.

This invention relates to an improved apparatus 10 constituting a feature of my patent on method of and apparatus for sizing paper, issued Aug. 22, 1916, No. 1,195,888.

The invention herein relates particularly 15 to improvements in the means for coating with size the upper surface of a web of paper stock passing between two cylinders, and provides for the more effective solution 20 of the problems presented by that part of the apparatus, namely, the difficulty of handling the soft paper stock, the disadvantage due to the fact that it tends to stick to the soft sizing cylinder and the fact that the surplus sizing is likely to be carried around 25 and interfere with the delivery of fresh sizing to the cylinder.

Reference is to be had to the accompanying drawings in which—

Figure 1 is an end view partly diagrammatical of the mechanism by which the sizing 30 is applied to a web of paper constructed in accordance with a preferred embodiment of this invention;

Fig. 2 is a plan of the same, and

Fig. 3 is a transverse sectional view on 35 enlarged scale.

The method of sizing is the same as that set forth in my above mentioned patent, and the apparatus is the same in principle, the differences being in the relative arrangement 40 of the parts and details of construction. In fact the sizing of the lower side of the web is done exactly as shown in the above mentioned patent by means of a hard surfaced cylinder 10 operating in a trough of size 12 45 and having a wiper or scraping blade 15 for removing the surplus on the supply side thereof. The surface of this cylinder may be of metal, wood or other hard material. It is found in practice to coat the under 50 surface of the web in a satisfactory manner because any surplus of sizing is squeezed back between the rolls and does not inter-

fere with the application of sizing to the web or admit of the application of too much sizing.

According to this invention the upper surface of the web is coated directly by what I call a soft cylinder 11. This cylinder is made with a relatively soft surface, preferably rubber. The web is led to this cylinder over a hard metallic or wooden roll 16 and the surface to be coated by this roll is brought into contact with it between the two rotary members 11 and 16. Then in order to prevent the web from having too great a surface contact with the cylinder 11, and also to insure a more even coating, it is carried directly away from the surface of this cylinder around a small roll 17 and then back to the cylinder at a short distance only 70 from the point of contact of the two cylinders 10 and 11. This insures that the surface of the web shall be intimately coated throughout its width on account of bringing the coated surface over the roll 17 and 75 does not admit of keeping the web in contact with the cylinder too long a period of time.

The coating of the cylinder 11 is shown as being done in the following way. The 80 sizing material, preferably feculose as stated in my above mentioned patent, is held in a trough 18 which is supported by the frame of the machine in a manner not necessary to describe in detail. This trough supports 85 a pair of movable deckles 19 which can be adjusted toward and from the center of the trough and support a plate 20 from which extends a flexible apron 21. This apron extends substantially throughout the length 90 of the surface to be coated. This apron may be formed of any desired flexible material, but I have found patent leather to be very suitable for the purpose.

I have shown also two rubber air pipes 95 22 at the two ends of the apron movable with the deckles and having a lead or tin lining. They have air discharge passages on their inner sides for forcing inwardly the edges of the film of size deposited on 100 the cylinder to spread it between the tubes and keep it in that space. This size feeds by gravity from the trough 18 through holes 23 on the apron and passes up the side of

the cylinder where it comes into contact with the web. It is squeezed on this web between the roll 16 and the cylinder 11 which spreads it out to substantially its original width on 5 the web, that is the full width of the web. The web is then separated almost immediately from the surface of the cylinder 11 where the wet side passes over the roll 17, which further spreads the coating and 10 makes it more homogeneous on the web. Then it passes back to the surface of the cylinder and is pressed between this cylinder and the cylinder 10 at the time when the other side is coated by the latter. For cleaning 15 the cylinder 11 a doctor roll 24 is located in contact therewith between the point at which the web is delivered from it and the point at which the sizing is delivered to it. This takes surplus sizing from the cylinder 20 so as to present a clean surface to the sizing delivery device. The doctor is cleaned by a blade 25.

It will be understood, of course, that this process is applied to a web of paper or paper 25 stock in substantially the condition and the period in its manufacture represented in my above mentioned patent, matters set forth therein not being repeated here for obvious reasons. This web has not the consistency 30 of completed paper however and therefore ordinary coating methods are not applicable. By this arrangement the upper surface of the soft web can be coated uniformly and rapidly.

35 Although I have illustrated and described only a single embodiment of the invention, I am aware of the fact that many modifications can be made therein by any person skilled in the art without departing from 40 the scope of the invention as expressed in the claims. Therefore I do not wish to be limited to all the details of construction

herein shown and described, but what I do claim is:—

1. In an apparatus for sizing a web of 45 paper stock during the manufacture of the paper, the combination with a hard cylinder running in a trough of size for coating the under side of the web, a soft surfaced cylinder running substantially in contact therewith for coating the upper surface of the same web, means for coating the soft cylinder with size, and means for first bringing the web firmly in contact with the soft surfaced cylinder but thereafter separating the 50 web from that cylinder and bringing it back to it and passing it between the two cylinders.

2. In an apparatus for sizing the upper 60 surface of a web, the combination of a sizing cylinder, means for delivering a film of size to the surface of the cylinder, means for then bringing the web into contact with said sized surface of the cylinder, means for then removing the web from contact with the cylinder, and later bringing it into contact with it at the bottom thereof, and means for pressing the web against the cylinder just before it leaves the surface thereof.

3. In an apparatus for sizing a web of 70 paper stock, the combination with a cylinder, of means for coating the surface of said cylinder with size, means for bringing a web to be coated into contact with the surface of said cylinder at a point on said surface to 75 enable the size to be applied directly to the web by the cylinder, means for then taking the web out of contact with the cylinder, and means for thereafter pressing it against the cylinder and directing it away from its surface.

In testimony whereof I have hereunto affixed my signature.

HENRY M. WHEELWRIGHT.
